UNITED STATES PATENT OFFICE.

JUDSON L. THOMSON, OF SYRACUSE, NEW YORK.

COMBINED WHIP-SOCKET AND REIN-HOLDER.

SPECIFICATION forming part of Letters Patent No. 274,675, dated March 27, 1883.

Application filed June 13, 1882. (No model.)

To all whom it may concern:

Be it known that I, JUDSON L. THOMSON, of Syracuse, in the county of Onondaga, in the State of New York, have invented new and useful Improvements in Whip-Socket Attachments and Rein-Holders Combined, of which the following, taken in connection with the accompanying drawing, is a full, clear, and exact description.

10 This invention consists in novel devices for securing the whip-socket to the dash-board, and also consists in a peculiar construction of a rein-holder combined with said whip-socket attachment, all as hereinafter more fully described, and specifically set forth in the claims.

The invention is fully illustrated in the annexed drawings, wherein Figure 1 is a side view of a whip-socket and its attachment to the dash-board, a portion of the whip-socket 20 being broken away to show the rein-holder. Fig. 2 is a view of the same from the rear of the dash-board; and Figs. 3 and 4 are horizontal transverse sections, respectively on lines *x* and *y*.

25 Similar letters of reference indicate corresponding parts.

D designates the dash-board, consisting of a metal frame and a leather panel secured to said frame and covering the same in the usual 30 manner.

S denotes the whip-socket, of any ordinary style. This socket is arranged immediately back of the end rail, *r*, of the dash-board frame, and between them is placed a block, *E*, fitted 35 neatly in its position, with a good bearing on both the whip-socket and rail *r*. The three parts *r*, *E*, and *S* are united by means of a metallic strap, *a*, extended around the rear of the whip-socket and around the outer face of the 40 rail *r*, underneath the leather *b*, and terminating with overlapping ends at the side of the block *E*. Transversely through the block *E* passes a bolt, *c*, having at one end an eye, *e*, through which the strap passes. The opposite end of said bolt is provided with a screw-threaded axial cavity or socket, *v*, in which works a screw, *u*, which passes through eyes in the overlapping ends of the strap, and has a head bearing against the exterior of the same. 45 The sides of the block *E* are made concave, so as to allow the strap to be drawn together be-

tween the whip-socket and dash-board, which is effected by tightening the screw *u*. This draft on the strap *a* firmly clamps the whip-socket in its position.

I am aware that whip-sockets have been attached to the dash-board by means of a strap passing around and fastened together between the socket and support by a rivet; but such devices do not afford the facility nor the adjustability of the attachment of the whip-socket obtained by my invention. The fastening of the strap by means of a rivet cannot be easily accomplished, owing to the want of a proper rigid support for resisting the requisite force 55 for upsetting the rivet, and a rivet clinched or upset at opposite ends does not admit of taking up any slack that may occur in the strap. Said defects are effectually obviated by the employment of the bolt *c*, in conjunction with 60 the screw *u*, hereinbefore described, which greatly facilitates the attachment of the socket and admits of taking up the slack of the attaching-strap and tightening the same when required.

75 It will be observed that by passing the strap *a* underneath the leather covering of the rail *r* in the manner described and shown I maintain the leather on the outside of the dash-board intact, and thus preserve the finish of 80 the dash-board. From the top of the block *E* is extended an arm, *f*, rigidly secured or cast on said block and lying close to the rear of the dash-board. From the end of the arm *f* projects horizontally nearly or quite at right 85 angles another arm, *f'*, from the free end of which projects vertically a post, *l*. The arm *f'* has as its junction with the arm *f* a vertical pintle, *g*, on which is hinged a gate, *h*, having between its hinged connection an opening 90 of sufficient size to allow a spiral spring, *k*, to be wound around the intermediate portion of the pintle. The upper end of this spring is made to bear on the back of the gate *h*, and the lower end of the spring is inserted in a hole in 95 the arm *f*, or otherwise firmly secured. The gate *h* is provided with two vertical lips, between which is clamped a rubber block, *i*, the free edge of which is in proximity to the post *l*. One of the aforesaid lips *o* is extended 100 nearly to the edge of the rubber block, so as to effectually support the same without depriv-

ing it of its rubber face. The spring *k* normally forces the gate in the direction from which the rein to be held is applied to the rein-holder. A stop or guard, *m*, projecting upward 5 from the arm *f'* and encountering the gate *h*, prevents the same from swinging past the post *l* and thus loosing its hold on the rein. The rein is applied to the described rein-holder by passing the rein between the post *l* and adjacent edge of the gate *h* from the guarded side 10 thereof. The gate, being allowed to swing away from the guard and post, admits applying the rein as aforesaid.

Having described my invention, what I claim 15 as new, and desire to secure by Letters Patent, is—

1. The combination, with the whip-socket *S* and dash-board *D*, of the interposed block *E*, the strap *a*, extended around the socket *S* and 20 around the rail *r*, and terminating with overlapping ends at the side of the block *E*, and the bolt *c*, passing through said block, and provided at one end with the eye *e* and at the opposite end with the screw-threaded socket *v*, 25 and the screw *u*, passing through the two ends

of the strap and into the socket *v*, substantially in the manner shown and set forth.

2. The rein-holder arm *f*, cast on or integral with the block *E*, in combination with the strap *a* and clamp-bolt *c*, substantially as shown 30 and set forth.

3. In combination with the strap *a*, the block *E*, having integral with it the arm *f*, the vertical pintle *g*, and horizontal arm *f'*, projecting from the end of the arm *f*, the post *l* on the free 35 end of arm *f'*, the gate *h*, provided with the block *i*, the spring *k*, wound around the pintle and pressing on the back of the gate, and the guard *m*, projecting from the arm *f'* in front of the gate, all constructed and combined substantially in the manner described and shown. 40

In testimony whereof I have hereunto signed my name and affixed my seal, in the presence of two attesting witnesses, at Syracuse, in the county of Onondaga, in the State of New York, 45 this 31st day of May, 1882.

JUDSON L. THOMSON. [L. S.]
